Attorney

UNITED STATES PATENT OFFICE.

JAMES EARL BECK, OF MECHANICSBURG, PENNSYLVANIA.

ILLUMINATED ORNAMENTAL DEVICE FOR DECORATIVE PURPOSES.

Application filed March 16, 1928. Serial No. 262,198.

My invention relates to electrically illuminated ornamental devices for decorative purposes and particularly for use on Christmas trees and the like.

5 The particular embodiment of my invention, as illustrated in the drawings and described herein, comprises a star shaped figure particularly adapted to be placed on top of a Christmas tree, although it may obviously 10 be arranged on other places thereon; or arranged within a wreath, the device being provided with means for securing the same in place.

The object of my invention is to provide an 15 ornamental device comprising a base or body portion equipped with a plurality of suitably arranged electric bulb sockets, so that the bulbs will complete the design, and further equipped with means to facilitate securing the 20 device in the desired position. A further object of my invention is to provide a device as mentioned in which access may be readily had to the sockets, and the circuit connecting the same to facilitate assembly and repair. A 25 further object of my invention is to provide a device as mentioned equipped with devices adapted to be selectively arranged thereon for securing the device in the desired position. Other objects will appear hereinafter.

30 With these objects in view my invention consists generally in a base or body portion one face thereof being shaped and equipped to constitute a reflector, a bulb socket arranged to hold a bulb within said reflector and a plurality of radially arranged sockets on said body portion. My invention consists in a device as mentioned in which all of said sockets are permanently connected in series and in which the body portion is formed of two detachable sections with the sockets and connections detachably arranged between them. My invention further consists in a device as mentioned in which the terminals of the circuit connections are arranged to be engaged by the 45 contacts or an ordinary separable plug. My invention further consists in a device as mentioned equipped with a plurality of attaching devices arranged at intervals about the periphery of the body portion. My invention 50 further consists in a device as mentioned in which the attaching means are readily removable in order that only those necessary for securing the device may be used. My invention further consists in various details of construction and arrangements of parts all as will be

fully described hereinafter and particularly pointed out in the claims.

My invention will be more readily understood by reference to the accompanying drawings forming a part of this specification and in which—

Figure 1 is an elevation of an ornamental device embodying my invention in its preferred form,

Fig. 2 is a section on the line 2—2 of Fig. 1, 65
Fig. 3 is a plan view of the rear element of the body portion, and

Fig. 4 is an elevation of the detachable sockets and connections removed from the body portion. 70

In carrying out my invention the preferred form of the device is that of a star. This consists of a preferably circular body portion having arranged adjacent its periphery a plurality of sockets to receive electric bulbs and hold them in radiating position. As above stated the device is particularly adapted for use on Christmas trees, and for arrangement within wreaths. It is customary in the illumination of Christmas trees to use the ordinary house current and provide a plurality of small lights in series. The ordinary Mazda bulbs used for this purpose are tapering or conical in form and are well adapted to form points of a star. 80

Referring now to the drawings 1 indicates the base or body portion of the device which is preferably formed of insulating material. The body is preferably cylindrical, and is formed of a front section 2 and a rear section 3 detachably connected by a plurality of screws 4 extending through the rear member 3 and threaded into bushings 5 secured to the rear face of the front section. Only one of the screws 4 are illustrated although any number may be employed. In the form illustrated I preferably use five such screws, and the rear section 3 is perforated with a corresponding number of holes 6 to receive them. A plurality of radially arranged sockets 7 are positioned between the sections 2 and 3, said sections being correspondingly recessed as at 8 and 9 respectively to receive them. 10 indicates the tapered electric bulbs arranged within the sockets and forming the 105 points of the star. The front of the section 2 is concavely formed as at 11 and the concave face is suitably treated to form a reflector. Centrally arranged within the body is a socket 12 by means of which a bulb 13 is held 110

in position within the reflector 11. The body sections are formed with apertures 12' for the socket 12. This socket is arranged axially of the body portion as illustrated. The 5 sockets 7 and 12 are connected in series, as illustrated clearly in Fig. 4, 14 indicating the connecting conductors. The inner face of the rear section 3 of the body is formed with corresponding recesses 15 to receive the 10 conductors.

The socket 12 is provided with a rearwardly extending spring contact terminal 16 and one of the sockets 7 is provided with a similar terminal contact 17. The contacts 16 and 15 17 are arranged within suitable recesses 18 formed in the rear section 3 and are adapted to be engaged by the terminal contacts 19 of an ordinary separable plug 20. It is obvious that access may be readily had to the 20 sockets 7 and 12 by removing the screws 4 and separating the sections 2 and 3. This construction facilitates the assembly of the devices and also the removal of the sockets and their connections as a whole for the purpose 25 of repair, should it become necessary.

Means are provided for securing the device in position. To this end I provide a plurality of eyelet members 21 to which wires or other devices may be attached for securing 30 the ornament to a tree or within a wreath. It is obvious that the number of eyelets 21 necessary for securing the device in position will vary; and in order that only the requisite number shall be employed I make the 35 eyelets detachable. To this end said eyelets are formed with inwardly extending stems 22 terminating in eyelets 23 similar to the eyelets 21. These are arranged in recesses 24 formed in the faces of the body members;

and are positioned so that the screws 4 extend through the eyelets 23. It is obvious that by this construction the desired number of attaching devices may be employed and the others removed so as to avoid being unsightly. 40

I claim:

1. A device of the class described comprising a body portion, one face of the body portion constituting a reflector, a bulb socket arranged axially thereof, and a plurality of 50 radially disposed bulb sockets arranged with their bulb receiving ends at substantially the periphery of the body portion, substantially as described.

2. A device as set forth in claim 1 further 55 characterized by conductors connecting the several sockets in series and fixedly spacing the same from each other, and in which the body portion is formed of front and rear sections detachably connected, the adjacent 60 faces of said body sections being provided with recesses to removably receive said sockets and conductors, substantially as described.

3. In an illuminated ornamental device, a 65 body portion formed of front and rear sections and provided with a plurality of bulb sockets in combination with a plurality of members detachably connecting the said sections and securing devices arranged between 70 said sections and projecting from the periphery of the body portion, and removably secured thereto by the members connecting the said sections as and for the purpose specified.

In testimony whereof I have signed my 75 name to this specification.

JAMES EARL BECK.
